UNITED STATES PATENT OFFICE.

GEORGE W. LANGFORD, OF ANN ARBOR, MICHIGAN.

SELF-CLOSING RECEPTACLE.

Application filed March 20, 1922. Serial No. 545,022.

The invention relates to self-closing receptacles and has for its object the provision of a receptacle having an inwardly opening door which in its normal position, closes 5 the receptacle and at the same time extends beyond the upper edge of the receptacle body, whereby the receptacle is made both fireproof and weatherproof. With this and other objects in view, the invention resides 10 in the novel features of construction as more fully hereinafter set forth.

In the drawings:

Figure 1 is a side elevation of a receptacle embodying my invention;

15 Figure 2 is a side elevation at right angles to Figure 1 and partly in section;

Figure 3 is a top plan view thereof;

Figure 4 is a side elevation partly in section of a modified construction of receptacle.

The receptacle has the body 1 having the open upper end and the top 2 hinged to one side of the body at 3. The top comprises the upwardly converging side members 4, the inwardly swinging doors 5 closing openings in opposite side members, and the cap 6 having depending flanges 7 to which the upper ends of the side members are fixedly secured and the upper ends of the doors are pivotally secured as at 8. The cap has a flat upper face 9 to which may be secured a street sign or the like. The doors 5 underlie the edge portions of the side members and normally close the openings therein.

35 To hold the doors in normally closed position, they are pivotally connected near their lower ends to the like links 10 and 11, the adjacent inner ends of which are pivotally connected to the counter weight 12 which is sufficiently heavy to close either door or both doors at the same time.

For the purpose of making the receptacle weatherproof, the side members 4 as well as the doors 5 of the top extend near their 45 lower ends laterally beyond the upper edge of the receptacle body 1, the side members terminating at their lower ends in inwardly extending flanges 13 which extend over the upper edge of the body. The doors have at their lower ends the inwardly extending flanges 14 spaced sufficiently above the inwardly extending flanges 13 of the side members to clear the latter upon inward swinging of the doors. These inwardly extending flanges 14 upon the doors terminate in depending flanges 15, which latter are

adapted to engage the inner sides of the body 1 when the doors are in normally closed position. To close the gaps formed between the inwardly extending flanges 13 and 14 thereby making the receptacle more thoroughly fireproof and weatherproof, I have provided the sealing strips 16 secured to the inwardly extending flanges 13 and adapted to be slidably engaged by the side 65 edges of the inwardly extending flanges 14.

In the modified construction shown in Figure 4, the doors 17 are moved into their normally closed positions by means of the separate weights 18 rigidly secured to the 70 doors by the inwardly extending arms 19. The inwardly extending flanges 20 at the lower ends of the frame members 21 of the top and also the inwardly extending flanges 22 at the lower ends of the doors 17 are 75 curved to be concentric with each other about the respective pivots 23 of the doors, the arrangement being such that the inwardly extending flanges of the doors slidably fit the inwardly extending flanges of 80 the side members of the top. The doors also have the depending flanges 24 upon the inwardly extending flanges 22 and adapted to engage the inner sides of the receptacle body when the doors are in normally closed 85 position.

From the above description, it will be readily seen that I have provided a receptacle having an inwardly swinging door which is normally in closed position, the 90 top of the receptacle including the side members and the door extending laterally beyond the upper edge of the receptacle body to weatherproof the same.

What I claim as my invention is:

1. In a receptacle, the combination with a receptacle body, of a top comprising side members extending near their lower ends laterally beyond said receptacle body, one of said side members having an opening 100 therein and an inwardly swinging door normally closing said opening and extending near its lower end laterally beyond said receptacle body and terminating in a depending flange adapted to extend into said 105 receptacle body when said door is in its normally closed position.

2. In a receptacle, the combination with a receptacle body, of a top comprising side members extending near their lower ends 110 laterally beyond said receptacle body and terminating in flanges extending inwardly

over the upper edge of said body, one of said side members having an opening therein, and an inwardly swinging door normally closing said opening and extending near 5 its lower end laterally beyond said receptacle body and having an inwardly extending flange spaced above the inwardly extending flanges of said side members, and means for closing the spaces between said 10 inwardly extending flanges upon said door and side members.

3. In a receptacle, the combination with a receptacle body, of side members extending near their lower ends laterally beyond 15 said receptacle body and terminating in flanges extending inwardly over the upper edge of said body, one of said side members

having an opening therein, and an inwardly swinging door normally closing said opening and extending near its lower end laterally beyond said receptacle body and having an inwardly extending flange terminating in a downwardly extending flange adapted to engage the inner side of said receptacle body when said door is in its normally closed position, said inwardly extending flange being spaced above said first-mentioned inwardly extending flanges, and means for closing the spaces between said flanges. 20 25 30

In testimony whereof I affix my signature.

GEORGE W. LANGFORD.
